A. R. ACKERMANN

BASSINET

Filed May 5, 1925

Inventor
Alois R. Ackermann

Attorney
Herbert E. Smith

UNITED STATES PATENT OFFICE.

ALOIS R. ACKERMANN, OF SPOKANE, WASHINGTON.

BASSINET.

Application filed May 5, 1925. Serial No. 28,134.

To all whom it may concern:

Be it known that I, ALOIS R. ACKERMANN, a citizen of Switzerland, residing at Spokane, in Spokane County and State of Washington, have invented certain new and useful Improvements in Bassinets, of which the following is a specification.

The present invention relates to an improved bassinet or child's crib and is designed for the purpose of providing an article of this type which may with facility be converted for use in various ways in caring for a child.

The invention contemplates the use of a supporting or suspending frame for the bassinet in which the latter may be suspended in fixed stationary position, readily converted for swinging or rocking movement, or the bassinet may be bodily removed if desired and become a portable carrier for the child.

The invention consists in certain novel combinations and arrangements of parts for carrying out the above indicated purposes and the device involves features of construction by means of which the finished article may be produced at comparatively low cost of production, as will hereinafter be more fully pointed out.

In the accompanying drawings I have illustrated one complete example of the physical embodiment of my invention wherein the parts are combined and arranged in accord with the principles of my invention.

Figure 1 is a perspective view of a bassinet embodying my invention.

Figure 2 is an enlarged vertical central sectional view, partly broken away for convenience of illustration.

Figure 3 is a detail sectional view, enlarged of the support at the head of the bassinet.

Figure 4 is a sectional detail view enlarged of the support at the foot of the bassinet.

In carrying out my invention I preferably use a suspending frame made up of tubular metal pieces or pipe lengths which are ornamented as desired, and the frame includes a base portion comprising a pair of transversely arranged, parallel tubular bars 1 and 2 spaced the required distance apart, and provided with ends bent to vertical position and equipped with castors 3 by means

of which the device as a whole may readily be moved.

A longitudinally extending horizontal brace bar 4 unites the transverse bars and suitable joint devices are employed for making rigid joints in this base frame.

At one end of the base frame a head post 5 is secured and at the opposite end a foot-post 6 is fixed, both posts standing erect and perpendicular to the base frame and made up of pipes or tubular lengths.

At the upper end of the head post 5 I provide a coupling head 7 in the form of a hollow casting screwed on the upper threaded end of the post, and this head is fashioned with an internally threaded flange 8 projecting laterally from the head. The flanged head carries a screw bar 9 preferably fashioned with a hand wheel 10.

At the upper end of the foot post I arrange a fixed angular head 11 which forms a trunnion alined with the screw bar at the opposite end of the suspending frame of the bassinet indicated by the numeral 12.

The bassinet is of suitable construction and lined or padded as usual. It is capable of being fixed in the frame, adapted to be converted to a swinging or rocking motion in the frame, or the bassinet may be detached and bodily removed from the frame to be used as a carrier for the child.

The bassinet is provided with a supporting frame in the form of horizontal central metal plates or straps as 13, 14 and 13' and 14' at the respective ends of the basket and which are secured thereto in suitable manner for supporting the basket.

The frame section 13 is provided with a bracket 15 secured thereto at the top edge of the basket and this bracket is fashioned with a threaded cup or nut 16 for the short end 17 of the screw bar 9 which is used to couple the basket to the head post.

At the foot of the basket and attached to the frame section 13' is a complementary bracket plate 18 having a bearing cup 19 alined with the nut 16 at the head end of the basket. As seen in Figure 2 this bearing cup is designed to receive the smooth portion 11^a of the angle head 11 that forms a supporting trunnion for the foot end of the bassinet, and a cotter pin 20 may be passed through registering holes in the cup 19 and trunnion 11^a of the head 11 to secure the basket or bassinet in stationary position.

in its suspending frame. The cotter pin is carried at the end of a retaining chain 21 fixed to the bassinet to insure against loss of the pin.

5 From the above description it will be seen that the basket is supported at its opposite ends by means of the screw bar 9—17 and its connections and the trunnion 11^a and bearing cup 19, with the cotter pin 20 holding 10 the bassinet in stationary position. If it is desired to convert the basket for a rocking or swinging motion, the pin is removed and the basket may be swung on its threaded and smooth trunnions.

15 With the cotter pin removed, for the purpose of bodily removing the basket from its frame, the basket may be detached by turning the hand wheel 10 to screw the bar 9 into the long flange or nut 8 and out of the 20 shorter flange or cup 16, and then the cups 9 and 16 may be grasped as handles and the bassinet carried to its destination.

The bassinet may be replaced and again suspended in its frame by first slipping the 25 cup 9 over its trunnion 11, and then running the screw bar into the threaded cup 16.

For convenience in lighting or illuminat-

ing the crib when attending to the occupant, and for supporting a canopy over the bassinet, I use an adjustable rod 22, preferably 30 hollow, and inserted in the tubular head post, where it may be clamped in adjusted position by the set screw 23.

A lamp and shade 24 may be supported at the end of this bend rod, and wires 25 35 may lead to the lamp through the tubular post and adjustable rod.

Having thus fully described my invention what I claim as new and desire to secure by Letters Patent is—

40 The combination with a supporting frame comprising a head post having a screw bar and hand wheel thereon and a foot post having a perforated trunnion thereon, of a bassinet having frame sections attached thereto, a bracket on one frame section having a nut to receive said screw bar, a bracket on the other frame section having a bearing cup for said trunnion, said bearing cup having a perforation therethrough, and a cotter 45 pin for securing said cup and trunnion. 50

In testimony whereof I affix my signature.

ALOIS R. ACKERMANN.
